AUTOMATIC TRAIN PIPE CONNECTOR

Joseph Robinson, New York, N. Y., assignor of
one-half to Roy M. Wolvin

Application April 9, 1935, Serial No. 15,458

6 Claims. (Cl. 285—58)

This invention relates to automatic train pipe connectors, and has among its objects to provide novel means for yieldingly supporting the connector head and for facilitating its coupling operation. The construction and advantages of my improvement appear from the following description and in the accompanying drawing, in which

Figure 1 is a fragmentary sectional side elevation of my improved means for yieldably supporting a connector head. In this view the forward part of the supporting means and the coupling head are not shown;

Figure 2 is a sectional plan view of the parts of my improvement which are omitted in Figure 1;

Figure 3 is a sectional front elevation on about the line 3—3 of Figure 1, and

Figure 4 is a front elevation of the construction shown in Figure 1 broken away just below the horizontal pivot 120.

Referring to the drawing: My improved automatic connector support places the buffer spring J to one side of and preferably above the longitudinal axis of the connector, and includes a novel means for removably securing the conduit 2 in the connector head A. A housing or hollow bracket K, having a reinforced rib 114 is forked at its forward end to straddle the coupler lug 84 to which it is secured by bolts or rivets 115. This bracket extends rearwardly of the lug, preferably horizontally, a substantial distance, and at its rear end is provided with a flat inclined portion or seat 116 of suitable transverse length. Through this seat I pass a tie rod 117 which extends forwardly to a position near the rear side of the lug 84. At this point I provide the bracket or housing K with a pair of inwardly extending lugs 118 on which to rest this side of the tie rod 117 and to support it and its associated parts as shown. Near its rear end I provide the housing K with a pair of downwardly extending lugs 119 between which I pivotally mount, as by the horizontally arranged pivot pin 120, a rocker arm 121. The upper portion of this arm comprises a suitably shaped head 122 having a flat rear surface which normally rests against the inclined seat 116. On its front face, and above the pivot 120, the rocker arm is provided with a part spherical seat 123 in which a spring seat 124 is mounted for rocking movement thereon. The tie rod 117 passes through these parts, has ample clearance in the member 122, and a bearing 125 in the spring seat of sufficient depth to avoid undue wear. Surrounding the tie rod, and supported

at one end by the spring seat 124 and at the other end by the adjustable nut or abutment 126, I mount a suitable buffer spring J which is assembled with a suitable amount of initial compression. Below the pivot 120 the rocker arm 121 is provided with a paddle-like portion 127 of shape and thickness desired. Spanning this portion of the rocker arm, and securely pivoted to it by the pin or bolt 128 I provide an anchor or link member 129 having an upwardly inclined rear face 130 which normally bears against, and has supporting relation to, the complementary inclined rear face 131 of the rocker arm 121. Suitably secured to the member 129, as by threads and a pin 132, I provide a suitable steel tube L which is threadingly connected with and locked to the shank 8 of the coupling head A as at 135. The thread on the yoke or forward end of the tube L is of substantial length, and at its forward end the tube is slotted as at 136 to slidably receive the pin 137 which suitably fits in the head of the thrust or plunger pin 138. The head of this pin is provided with an annular seat against one end of which a spring 139 acts. The other end of the spring rests against a wall in the shank 8, through which wall the pin 138 passes and moves in a suitable bearing 140 therein. The purpose of the pin is to removably secure the conduit 2 in place by engaging the rear side of the conduit lug 6 and forcing the lug against the vertically retaining pin 7 as shown. This action of the pin 138 is produced by screwing the nut 141 forward, while extraction of the conduit 2 from the coupling head A is permitted by the reverse of this operation. It will be understood, of course, that the lock spring 139 shifts the pin out of engagement with the lug 6 as the nut 141 is retracted. The nut includes a portion 142 which extends over the pin 137 to prevent accidental disengagement of the latter from the head of the plunger 138, and it also includes a portion 143 which carries the wrench 144, a snap ring 143 being arranged in a groove in the portion 143, after the wrench 144 is put in place, to prevent displacement of the wrench. The portions or extensions 142 and 143 serve also to protect against damage the threads along which the nut 141 travels. When it is desired to remove the fitting 2 to replace a worn gasket 5, or for other reason, the wrench is slipped over the nut 141, and through the medium of a weighted handle 145 on the wrench, the nut is retraced along the yoke or pipe L sufficiently to fully release the lug 6 with respect to the retaining pin 7, after which the conduit 2 may be 55

readily removed. The reverse of this operation will assemble the conduit in the coupling head A and securely lock it therein. This arrangement of nut and wrench avoids the possibility of the handle 145 stopping in the wrong position when the pin 138 forces the lug 6 into the service position against the pin 7, which might result if the handle 145 were integral with the nut 141. In Figure 2 which is a plan view, the handle 145 is shown out of the normal position in order to better illustrate it. Ordinarily it hangs of course below the yoke or pipe L.

When a pair of connectors constructed according to the embodiment of my invention shown in Figures 1-4 inclusive come together in service, the tube L is pushed rearwardly, which rocks the arm 121 about its pivot 120 and causes the spring J to be compressed. During this movement the upper portion 122 of the rocker arm 20 moves forward away from the seat 116, and inasmuch as the bearing 146 of the rocker arm on the pin 120 curves horizontally as well as vertically the rocker arm is free to oscillate universally on the pin 120 when the flange or head 25 122 leaves the seat 116 as stated. While this change in the position of the parts is taking place under the coupling movement of the connector head A, the connection between the link 130 and the face 131 of the rocker arm is also being released, and becomes completely free when the rocker arm moves to the coupled position shown in dotted lines in Figure 1. The coupling head A is then free to pivot downwardly on the pin 128, it being always free to move upwardly about 30 such pin. It will be understood that when the rocker arm 121 is in the normal uncoupled position shown in full lines in Figure 1 the coupling head A and the yoke L are supported in the normal horizontal coupling position, and against 35 downward rotation on the pivot 128, by engagement of the parts 138 and 134, and that the coupling head A is centered laterally by engagement, under pressure of the spring J, of the flat flange or head 122 against the front face of the seat 116. It will also be understood that the 40 coupling head A may be moved laterally and downwardly from the normal uncoupled position subject to the resistance of the spring J. Thus this spring serves not only to retain the 45 gaskets 5, and the coupling head A in firm engagement when coupled, but also to support the uncoupled head A in the normal horizontal position for universal movement from such position. The length of the fin or paddle-shape portion 50 127 of the rocker arm, and the vertical width of such portion and of the link 129, and the fit between these parts, should be such as to prevent undue stress on any of the parts when the coupling head A is moved laterally or downwardly 55 from the normal uncoupled position, and such also as to prevent undue rotation of the head about its longitudinal axis.

The terms and expressions which I have employed in this application are used as terms of description and not of limitation, and I have no intention, in the use of such terms and expressions, of excluding any equivalents of the features shown and described or portions thereof, but recognize that various modifications are possible within the scope of the invention claimed.

What I claim is:

1. An automatic train pipe connector support comprising, in combination, a lug adapted to be mounted upon a car coupler, a bracket secured to said lug, said bracket extending rear-

wardly from the lug a substantial distance and provided at its rear end with a flat forwardly inclined seat, a tie rod extending through said seat and forwardly to a point adjacent to the coupler lug aforesaid, means on said bracket for supporting the forward end of said tie rod, a spring seat on the forward end of said tie rod and a second spring seat slidably mounted on said tie rod, a coil spring encircling said tie rod and interposed between said spring seats, 10 said second mentioned spring seat having a partly spherical portion facing rearwardly, a rocker arm pivotally mounted on said bracket with its pivotal axis located below the spring and tie rod aforesaid, said rocker arm extending upwardly from said pivot and having its upper extremity formed complementary to and interposed between the partly spherical portion of the second mentioned spring seat and the forwardly inclined seat on said bracket, said rocker arm also extending downwardly from its pivot and having a relatively thin horizontally elongated lower extremity provided with a forwardly and downwardly inclined rear face, a member pivotally secured to and embracing the lower extremity 20 of said rocker arm, said member being provided at its rear end with a face inclined complementary to the inclined rear face of the lower extremity of the rocker arm, and said member also extending forwardly from the rocker arm substantially horizontally and adapted to carry a connector head at its forward end.

2. An automatic train pipe connector support comprising, in combination, a lug adapted to be dependingly secured to a car coupler, a bracket secured to and extending rearwardly from said lug, a rocker arm pivotally mounted on said bracket and movable universally on its pivot, said rocker arm extending upwardly from its pivot and having means yieldably engaging the upper 40 extremity thereof for normally rocking said rocker arm in one direction about its pivot, means for limiting the rocking movement of the arm aforesaid, said rocker arm being extended below its pivot, a forwardly extending connector head 45 mounting member pivotally secured to the lower extremity of said rocker arm, means on said last mentioned member and the lower extremity of said rocker arm for limiting the pivotal movement of said member relatively to said rocker arm whereby to maintain said member in a substantially horizontal and forwardly thrusted position incident to the urging of the upper extremity of the rocker arm to the limit of its movement by the yieldable means aforesaid, and permitting free oscillation about the pivot in a vertical plane when the rocker arm is rocked in an opposite direction pursuant to the application of rearward thrust on the connector head mounting member.

3. In an automatic train pipe connector, in combination, a coupler lug or the like, a bracket extending rearwardly therefrom, a rocker member pivoted between its upper and lower ends upon the said bracket, spring means coacting 65 with the rocker member and including a spring, a spring seat having a ball and socket-like engagement with the upper end of the rocker member, a tie rod passing loosely through the upper end of the rocker member engaging the bracket 70 at one end, an abutment on the other end of said tie rod connecting with the spring at the end opposite the spring seat thereof, and a coupling head mounted upon the lower end of the rocker member.

4. An automatic train pipe connector as claimed in claim 3, combined with a horizontal member extending from the lower end of the rocker member and carrying the coupling head, said horizontal member comprising a link part pivoted to the lower end of the rocker member and having an abutment to engage the latter to limit the movement of the coupler in one direction relatively to the rocker member, said link part permitting free movement of the coupling head in an opposite direction, relatively to the rocker member.

5. A train pipe connector as claimed in claim 3, wherein the said bracket is hollow and forms a housing for the spring seat and the upper end of the rocker member, the said bracket at its rear end being formed with a surface inclining forwardly and downwardly and adapted to be engaged with the upper end of the rocker mem-

ber through the cooperation of the spring acting upon the spring seat.

6. An automatic train pipe connector of the class described, comprising, in combination, a supporting bracket, a rocker member pivoted between its upper and lower ends to said bracket, a coupling head carried by the lower end of the rocker member and spring means coacting with the upper end of the rocker member above its pivot point and comprising a spring, and a spring seat of ball-like structure engaging said upper end of the rocker member, said upper end of the rocker member having a seat-like portion to receive the ball-like portion of said spring seat, and means connecting the spring seat with the bracket and passing loosely through the upper end of the rocker member.

JOSEPH ROBINSON.
